ADHESIVE TAPE DISPENSER

Gerhard A. Ellestad, Rochester, N. Y.

Application April 28, 1937, Serial No. 139,526

11 Claims. (Cl. 206—59)

This invention relates to spools or holders for coils or rolls of tape and more particularly it has reference to spools or holders for dispensing pressure-sensitive adhesive tape.

Various kinds of adhesive tape are supplied to the trade on spools or holders about which the tape is helically wound. Pieces of tape are unrolled and cut off as desired and the outer end of the tape in the roll is usually pressed down onto the adjacent outer layer of the roll and is held there by adhesion of the sticky substance on the tape. When it is desired to use another piece of tape, the outer end of the tape in the roll must be raised off or pulled out of adhesive contact with the adjacent layer of tape. This may be done with the finger nail or with any suitable sharp instrument. If the tape is relatively thick, this operation can usually be accomplished without much trouble but when the tape is relatively thin, it is often very difficult to pull the outer end away from contact with the roll so as to enable the user to grasp the end to unroll a desired amount of tape. A pressure-sensitive adhesive tape made by coating a tacky substance on a relatively thin tape of transparent cellulosic material is now marketed under the trade-mark "Scotch Tape." Great difficulty is often encountered in freeing the outer end of such cellulose "Scotch Tape" because the tape is so thin and the outer end is so readily and securely held in adhesive contact with the adjacent layer on the roll.

One of the objects of my invention is to provide means whereby pressure-sensitive adhesive tape may be readily and conveniently dispensed from a roll. Another object is to provide means whereby the outer end of a roll of adhesive tape may be easily and conveniently withdrawn from adhesive contact with the adjacent layer of the roll. A further object is to provide a simple, yet efficient, device for freeing the outer end of a roll of adhesive tape from adhesive contact with the body of the roll. Still another object is to provide simple, yet efficient, means whereby a piece of coiled tape may be readily and easily severed from the roll. A still further object is to provide a simple device for a roll of adhesive tape which will afford means for freeing the outer end of the roll of tape from contact with the roll and will also afford means for severing a piece of tape from the roll.

These and other objects and advantages reside in certain novel features of construction, arrangement and combination of parts as will hereinafter be more fully described and pointed out in the appended claims.

Referring to the drawing:

Fig. 1 is a perspective view of a roll of adhesive tape showing one embodiment of my invention.

Fig. 2 is a central sectional view of same.

Fig. 3 is an enlarged fragmentary side view of the roll.

Fig. 4 is a fragmentary view showing a modification.

Fig. 5 is a sectional view thereof.

Fig. 6 is a fragmentary perspective view of another modification.

Fig. 7 is a front view thereof.

Fig. 8 is a side view of same.

Fig. 9 is a fragmentary side view of still another modification.

Fig. 10 is a sectional view thereof.

Fig. 11 is a sectional view through a roll of tape showing a still further modification.

One embodiment of my invention is shown in Figs. 1-3 wherein 15 indicates a tubular member, 20 preferably of cardboard, about which the pressure-sensitive adhesive tape 16 is helically wound. Secured in one end of tubular member 15, by frictional engagement or otherwise, is a plate 17 having a centrally disposed aperture 18 through which runs a flexible cable or string 19. An enlargement, such as a knot 20, on one end of the string keeps the latter from being pulled away from the plate 17 and yet allows relatively free movement with respect thereto. The string 19 extends along the edge of the roll of tape 16 and across the face of the roll under the outer layer or convolution 21 of the tape adjacent its outer end 22 and beyond the edge of the tape so as to provide a gripping portion 23 preferably terminating in a knot 24.

The layer 21 and end 22 are, of course, adhesively secured to the adjacent layer of tape so that string 19 is held under layer 21. When it is desired to free the end 22 so that it may be grasped to unroll a desired length of tape, it is only necessary to pull the portion 23 of string 19 away from the face of the roll. This operation frees the end 22 so that it may be grasped and, after a piece of tape has been severed from the roll, the string 19 is again placed under the outer layer of tape near its outer end, as shown in Fig. 1.

In the modification shown in Figs. 4 and 5, the string 19 extends from the center of plate 17 to 50 the edge of the roll of tape 16 where it is attached to the angularly bent portion 25 of the element 26. The element 26, which may be formed of a strip of metal or other suitable material, is positioned under the outer layer 21 ad-

55

5 jacent its outer end 22 and extends beyond the edge of the tape so that a handle or gripping portion 27 is provided. When it is desired to free the adhesively secured outer end 22 from the adjacent layer, the handle 27 is grasped and the element 26 is twisted or otherwise moved to free the end 22 of the tape. After a piece of tape has been severed from the roll, the element 26 is again positioned under the outer layer 21 adjacent 10 its outer end 22. If the element is formed of metal, one edge 28 may be beveled or sharpened so as to provide a cutting edge for severing the tape. The string 19' may be omitted but its use will prevent the loss or misplacing of element 26 15 so that greater convenience results.

20 A further modification is shown in Figs. 6-8 wherein the string 19 extends under the outer layer 21, just as in the form shown in Figs. 1-3, but in Figs. 6-8 the free end of string 19 carries a tape cutting or severing device 29 having two 25 downturned portions 30 and the upstanding serrated cutting edge portion 31. After the outer end 22 of the tape is freed, the desired length of tape may be unrolled and then severed by tearing against the serrated edge 31 of the device 29 which may be selectively placed on the roll as shown in Figs. 6-8. When the desired amount of tape has been removed, the string 19 is again placed under the outer layer 21 ready for subsequent use. The cutting device 29 may be made of sheet metal or any other suitable material.

30 In the modification shown in Figs. 9-10 the adhesive tape 16 is helically wound around the tubular member 15. A substantially U-shaped 35 element 40 straddles the outer face of the roll of tape with its side portions 41 extending inwardly towards the center of the member 15. Each side portion 41 has an inturned projection 42 extending into the end of tubular member 15 so that the two projections 42 extend towards each other and 40 substantially parallel to the axis of tubular member 15, as clearly shown in Fig. 10. The element 40 is preferably formed of sheet material and the dimensions of the parts are such that the element 45 40 is mounted for relatively free movement around the outer face or periphery of the roll, it being evident that the projections 42 keep the element movably attached to the roll of tape 16. Extending outwardly from the part 43, which 50 connects side portions 41 of element 40, is a projection 44 having a serrated cutting edge 45.

55 The element 40 is positioned on the roll of tape as shown in Fig. 9 so that the piece of tape 46, which has been unrolled for use, may be severed along cutting edge 45. Since the inner face of the tape carries the adhesive or tacky substance, it will be evident that after piece of tape 46 has been cut off, the adjacent portion 47 of the tape on the roll will be adhesively secured to the face 60 of projection 44. When it is again desired to use a piece of tape from the roll, the element 40 is moved away from the end 47 so that its adhesive contact with projection 44 is broken and the end 47 of the tape rendered available so 65 that it may be grasped by the hand to unroll the desired amount of tape. The element 40 is again brought into position as shown in Fig. 9, the tape severed on edge 45 and the end of the tape adhesively secured to projection 44 ready for the 70 next use. It will be apparent that the element 40 affords not only a cutting device for the tape but also provides a ready and convenient means for adhesively holding the end of the tape so that it can be easily rendered available when an 75 amount of tape is to be unrolled for use.

The modification shown in Fig. 11 is quite similar to that shown in Figs. 1-3 except that instead of using a string for freeing the outer end of the tape 16, a twisted, bendable wire 48 is employed. The twisted wire is secured to plate 17 on tube 15 by means of an eyelet member 49 which passes through a hole in the plate. The wire 48 is thus mounted for relatively free movement relative to the plate and the roll of tape so that the end 50 of the wire may be positioned under the outer layer of tape and used in the same manner as string 19 in the structure of Figs. 1-3.

From the foregoing it will be apparent that I am able to attain the objects of my invention and provide simple yet efficient means for use in connection with a roll or spool of adhesive tape so that the outer end of the tape in the roll may be rendered available. Great convenience will thereby result to the user and further convenience will be afforded through the use of the simple tape cutting devices which I have provided. Each form of my device is relatively simple in structure so that it can be cheaply and readily embodied in or attached to some of the rolls or spools of adhesive tape which are now on the market. My inventions may, of course, be applied to other types of spools or rolls and may be used with various types of pressure-sensitive adhesive tapes, such as those used for surgical 30 or electrical insulation purposes, for example. Other modifications may obviously be made without departing from the spirit of my invention.

I claim:

1. A spool of adhesive tape comprising a member about which the tape is wound and means for freeing the outer end of the tape which has been adhesively secured to the adjacent layer of tape, said means comprising an element extending outwardly from each side edge of the tape 40 and under the outer layer of tape adjacent its outer end whereby said outer end may be pulled away from the adjacent layer of tape by grasping one end of said element, the other end of said element being secured to said member by a flexible cable. 45

2. A spool of pressure-sensitive adhesive tape comprising a member about which the tape is wound, and a flexible cable having one end secured to said member, said cable extending 50 across the face of the tape and adapted to be adhesively secured under the outer layer of tape adjacent its outer end, whereby a pull on the free end of the cable will free the end of the tape, and a tape cutting device carried by the free end 55 of said cable and adapted to be positioned across the roll of tape so that a piece of tape may be torn off against the cutting edge of said device.

3. A spool of pressure-sensitive adhesive tape comprising a tubular member about which the 60 tape is wound, a plate secured to one end of said member, and means for selectively withdrawing the outer end of tape which has been adhesively secured to the adjacent layer of tape, said means comprising a string having one end secured substantially at the center of said plate, said string extending under the outer layer of tape adjacent its outer end and across and beyond the face of the roll of tape so that the free end of said string may be grasped and pulled so as to withdraw the outer end of the tape from adhesive contact with the roll. 70

4. A spool of holding pressure-sensitive adhesive tape comprising a cylindrical member about which the tape is wound, said member having an 75

end face, and a flexible element having one end secured to the end face of said member, said element extending across and beyond the surface of the coiled tape and adapted to be positioned under the outer layer of tape adjacent its end whereby the outer end of the tape may be pulled out of contact with the adjacent layer of tape by means of said flexible element.

5. A reel of holding pressure-sensitive adhesive tape comprising a member about which the tape is wound, and means for pulling out the outer end of tape which has been adhesively secured to the adjacent layer of tape, said means comprising an element constructed and arranged to be positioned under and across the tape adjacent its outer end, said element having an end portion projecting beyond the edge of tape so that it may be grasped by the hand, the other end of said element being connected to said member by means permitting a relatively free, loose movement with respect thereto.

6. In combination with a roll of relatively thin pressure-sensitive adhesive tape in which the outer end of the tape is in close adhesive contact with the adjacent layer of the tape after a portion of the tape has been dispensed, means for lifting the outer end of the tape from adhesive contact with the adjacent layer of tape to permit grasping thereof, said means comprising an element interposed between the outer end of the tape and the body of the roll, said element having a handle portion extending beyond the tape.

7. A spool of adhesive tape comprising a member about which the tape is wound in superposed convolutions, an element connected to the spool, said element being movably mounted on and in contact with the outer layer of tape, said element providing a relatively broad surface against which the outer end of the tape may be adhesively secured, said element having a cutting edge closely adjacent to said surface whereby the tape may be severed on said edge and the end of the tape adhesively secured to said surface and selectively freed from said surface by movement of the element.

8. A roll of relatively thin pressure-sensitive adhesive tape in which the outer end of the tape is in close adhesive contact with the adjacent layer of tape after a portion of the tape has been dispensed comprising a member on which the tape is helically wound, means for withdrawing

the outer end of tape from adhesive contact with the adjacent layer, said means comprising an element having a relatively broad surface on which the outer end of tape is adhesively secured, said element being movably mounted on and in contact with the roll whereby the adhesive contact between the end of the tape and the element may be broken by moving the element relatively to the end of the tape.

9. A roll of pressure-sensitive adhesive tape 10 comprising a member on which the tape is helically wound, means for withdrawing the outer end of the tape from adhesive contact with the adjacent layer of tape, said means comprising a relatively rigid element interposed between the 15 outer end portion of the tape and the body of the roll, a handle portion on said element projecting beyond the edge of the tape and flexible means connecting the element to said member.

10. A spool of relatively thin pressure-sensitive 20 adhesive tape in which the outer end of the tape is in close adhesive contact with the adjacent layer of tape after a portion of the tape has been dispensed comprising a member about 25 which the tape is wound, means for freeing the outer end of the tape which has been adhesively secured to the adjacent layer of tape to permit grasping thereof, said means comprising an element positioned under and across the tape adjacent its outer end, said element having a portion projecting beyond the edge of the tape so that it may be moved by the hand, said element also having a portion connected to said member by means permitting a relatively free, loose 30 movement with respect thereto.

11. A spool of relatively thin pressure-sensitive adhesive tape comprising a member about which the tape is wound in superposed convolutions, an element resting on and extending across the outer convolution of tape, said element being 40 connected to said member by means permitting a relatively free, loose movement relative to the spool and the layers of tape thereon, said element having a relatively broad surface against which the outer end of the tape may be adhesively secured but selectively freed therefrom by movement of the element, said element having a cutting edge closely adjacent said surface whereby the tape may be severed on said edge and the outer end secured to said surface.
